Primary Examiner — Kelley A Donnelly(74) *Attorney, Agent, or Firm* — Vorys, Sater, Seymour & Pease LLP; William Klima(57) **CLAIM**

The ornamental design for a crate, as shown and described.

DESCRIPTION

FIG. 1 is a top and front isometric view of a new design for a crate;

FIG. 2 is a bottom and rear isometric view thereof;

FIG. 3 is a front elevational view thereof;

FIG. 4 is a rear elevational view thereof;

FIG. 5 is a right side elevational view thereof; the left side elevational view being a mirror image of FIG. 5;

FIG. 6 is a top plan view thereof; and,

FIG. 7 is a bottom plan view thereof.

The broken lines shown in the drawings illustrate unclaimed portions and form no part of the claimed design.
